US00D601060S

(12) **United States Design Patent**
Kinoshita

(10) **Patent No.:** US D601,060 S
(45) **Date of Patent:** ** Sep. 29, 2009

(54) **FRONT FENDER FOR A FOUR-WHEELED MOTORCYCLE**

(75) Inventor: **Shogo Kinoshita**, Tokyo-to (JP)

(73) Assignee: **Yamaha Hatsudoki Kabushiki Kaisha**, Shizuoka-ken (JP)

(**) Term: **14 Years**

(21) Appl. No.: **29/324,119**

(22) Filed: **Sep. 5, 2008**

(51) **LOC (9) Cl.** 12-11

(52) **U.S. Cl.** D12/107

(58) **Field of Classification Search** D12/3, D12/86, 87, 107, 110, 181-186; 180/225, 180/229, 223, 233, 311, 312, 315; 296/77.1, 296/78.1, 180.1, 192, 193.01, 193.05, 193.08, 296/193.09, 198, 193.11; 293/102-104; 280/152.1-152.3, 847-852

See application file for complete search history.

(57) **CLAIM**

The ornamental design for a front fender for a four-wheeled motorcycle, as shown and described.

DESCRIPTION

FIG. 1 is a front right perspective view of a front fender for a four-wheeled motorcycle;

FIG. 2 is a right side view thereof;

FIG. 3 is a left side view thereof;

FIG. 4 is a front view thereof;

FIG. 5 is a top plan view thereof; and,

FIG. 6 is a bottom plan view thereof.

The broken lines showing other portions of a four-wheeled motorcycle are included for the purpose of illustrating environment only and form no part of the claimed design.
